EXPANSIBLE GROUNDING ELECTRODE

James D. Covington, Dallas, Tex., assignor, by
mesne assignments, to Socony-Vacuum Oil
Company, Incorporated, New York, N. Y., a cor-
poration of New York

Application April 17, 1950, Serial No. 156,389

5 Claims. (Cl. 174—6)

1

This invention relates to an electrode for readily establishing a high current circuit through a portion of the earth such as may be employed in electrical prospecting or electrical logging systems.

For example, in electrical prospecting methods such as generically illustrated by Patent No. 2,454,911 to Dayton H. Clewell, relatively high amplitude current flow is produced in the earth between two grounded electrodes. Potentials resulting from the current flow are measured at spaced points to define earth structure. In such systems, a low impedance current path through the earth permits most efficient use of associated equipment in producing measurable potentials. For such low impedance circuits, it has been found that the electrodes used should have as large a surface area as possible since the major portion of the resistance in the circuit is often in the electrode-ground contact. At the same time, it is desirable to keep the size of the equipment to a minimum. A physically small grounding electrode with large surface area suggests a plural surface or honeycomb device. Ordinarily, through repeated use, such devices collect foreign matter in the cavities that is so difficult to remove that the affected electrodes soon become unusable and must be discarded.

In accordance with the present invention, there is provided a folded or plural surface sheet metal electrode which has a large ratio of surface area to volume occupied thereby so constructed that it may readily be cleaned of mud and debris collecting therein.

In a preferred form of the invention, a rectangular metal plate is pleated normal to a length thereof. A terminal bar reinforcing is secured along one end of the plate and extends beyond one edge adjacent said end with electrical connector means carried by the extension. Means are provided for rigidly but releasably interlocking the ends of the pleated plate to form a crimped expandable electrode.

For further objects and advantages of the invention and for a more complete description thereof, reference may now be had to the following description taken in conjunction with the accompanying drawings in which:

Fig. 1 is a diagrammatic view of an electrical prospecting system;

Fig. 2 is an exploded view of the electrode; and

Fig. 3 is an isometric view of the electrode of the present invention.

2

In the electrical prospecting system of Fig. 1, current from a source generically represented by the generator 10 connected to current electrodes 11 and 12, suitably grounded, flows through the earth producing an effect at a measuring station 13 which is detected by a circuit including potential electrodes 15 and 16 and an indicating device generically represented by meter 17. The current from source 10 may be D. C., pulses, sine wave A. C., or may be otherwise modified in accordance with teachings of the prior art. In any case, it is desirable to have as much as possible of the energy from source 10 radiated for detection by the potential electrodes while accompanied by but small power loss due to the flow of the current in producing the effect desired to be measured. It is therefore necessary to provide low resistance current electrode-earth contacts in the exciting circuit thereby reducing the resistive losses and permitting high currents for radiation of signal energy.

Pits and holes filled with a highly conductive liquid, such as salt solution, have been utilized to lower the resistance between electrodes and the earth. Electrodes that may conveniently be placed in electrolyte filled auger holes have been provided which consist of a number of concentric copper tubes suitably connected together. However, deposits of heavy clays and other muds often characteristic of areas under survey are forced into the spaces between the electrode elements and are most difficult to remove. Such deposits substantially increase the initial contact resistance between electrode and ground. Further, when mud cakes are present, the contact resistance drifts toward equilibrium as the cake absorbs moisture. Ordinarily such variations in the resistance of the input current circuit cannot be tolerated.

40 By the present invention there is provided an electrode having large surface area of small volume for use in small diameter bore holes. The electrode is physically expansible for mechanically working the mud and debris loose 45 from the many folds that make possible the large area. The foregoing features will be more apparent by referring to Figs. 2 and 3.

A rectangular plate 20, Fig. 2, of low resistivity material is crimped or pleated uniformly 50 along a length thereof with the pleats normal to the length. The plate is crimped to relatively small angles, the internal angles, x , being preferably in the order of 30° . A latching bar 21 is provided with a hook 22 at one end. The hook 55 may conveniently be formed by bending the bar

21 back on itself as shown. A threaded lug or bolt 23 is secured to the other end of latching bar 21 and extends normal to the plane of the bar on the same side thereof as the hook portion 22. The bar 21 is then welded onto the end 24 of the plate 20 with the interior of the hook portion 22 even with the edge of the plate 20 and extending away therefrom.

A terminal bar 26 similarly is reinforcingly welded along the end portion 27 of plate 20. In the form shown, terminal bar 26 has a first extension 28 which includes or carries a handle and a second extension 29 which carries electrical connecting means generically illustrated by the lug 30 (shown in Fig. 3) inserted in hole 29a for readily interconnecting the electrode and a conductor extending from source 10 of Fig. 1.

With the construction above described, i. e., with the latching bar 21 and terminal bar 26 (of the exploded view of Fig. 2) welded to the adjacent end portions 24 and 27 respectively, the plate 20 may be bent to form a star-shaped or crimped tube. The end of plate 26 is placed in the hook portion 22 of the latching bar 21 and the bolt 23 passed through a hole 23a in the terminal bar 26. A wing nut 23b, shown in Fig. 3 only, threadedly engages bolt 23 to secure the interlock between the ends of the plate 20. It will be noted that the extension 28 of the terminal bar 26 is located approximately at the center of the star-shaped tube and extends radially therefrom through the root of one of the corrugations in the tube. The handle 31 carried by extension 28 is thereby located approximately at the axis of the electrode to balance the electrode when it is carried. With the ends of the electrode plate 20 thus interlocked, the electrode with relatively large radiating surface area may be placed in holes of relatively small diameter.

For a given volume occupied by the electrode, the number of points or crimps in the plate will determine the ratio of surface area to volume. This ratio numerically is a measure of the efficiency of a given electrode. By providing a large number of pleats or folds, the ratio becomes very large. At the same time, the difficulty of cleaning heavy clays ordinarily becomes more and more difficult. However, in accordance with the present invention, the electrode may be cleaned by removing the bolt 23 from hole 23a and disengaging the hook 22 whereupon the electrode may be opened or expanded. By merely shaking and mechanically working the expanded electrode, all of the inhibiting clays and debris may be readily removed. As the electrode is opened from the folded form as illustrated in Fig. 3 to a form substantially as illustrated in Fig. 2, the clays adhering to the internal angular surfaces automatically are freed from the two adjacent surfaces. Thereafter, the plate may be again bent to tubular form and interlocked for further use.

In one form of the invention, the plate 20 was of 16 gauge sheet copper approximately 10 inches wide. The latching bar 23 and the terminal bar 26 were $\frac{1}{8}$ inch copper strips, being heavier than plate 20 to reinforce the plate at the latching points. It will be apparent that the crimped plate could itself be formed to include a suitable latching element and thus dispense with the use of the reinforcing bars. For ease of fabrication, the use of a separate latching bar and terminal bar will be preferred since the stock may be sheared without having to form irregular edges. Further, for repeated use, added strength at

points vulnerable to impact will be found to be highly desirable.

While a preferred embodiment of the invention has been described, it will be understood that further modifications may be made without departing from the spirit and scope of the invention as set forth in the appended claims.

What is claimed is:

1. An electrode comprising a rectangular metallic plate pleated normal to the length thereof, a terminal strip reinforcingly secured along one end of said plate at an angle with respect to the mean plane of said pleated plate, means for releasably interlocking said strip and the other end of said plate with said terminal strip directed inwardly thereof to form an expansible electrode having a high ratio of surface area to volume, and means for coupling an electrical circuit to said electrode.
- 10 2. A low resistance electrode comprising a rectangular plate pleated normal to the length thereof, a latching bar reinforcingly forming one end of said plate and extending beyond one edge of said plate adjacent said end, a hook on said extended end of said bar for interlocking said bar and the other end of said plate, a fastening device locking the ends of said plate at the edge opposite said hook for securing the interlock between said ends to form an expansible electrode having a large ratio of surface area to volume, and means for connecting an electrical conductor to said electrode.
- 15 3. An electrode which is readily cleaned and which has a large ratio of surface area to volume comprising a rectangular metallic plate pleated normal to the length thereof, a terminal bar reinforcingly forming one end of said plate and extending beyond one edge adjacent said end, electrical connecting means and carrying means
- 20 35 connected to the extension of said bar, a hook at the edge of said plate opposite said extension for interlocking said bar and the other end of said plate, and releasable fastening means at the edge of said plate opposite said hook for securing said interlock to form a rigid expansible electrode.
- 25 4. An electrode having a large ratio of surface area to volume which is readily cleanable comprising a corrugated star-shaped tube, a terminal bar extending longitudinally through said tube from the axis thereof through the root of one of the corrugations with longitudinal sections of said corrugated tube folded outwardly facing opposite sides of said bar, means for bending said bar to one of said folded sections, a hook at the
- 30 40 45 end of said plate and at one edge thereof for interlocking said folded sections at said edge, releasable fastening means at the edge of said folded sections opposite said hook for securing said interlock to form a rigid expansible electrode, and means for connecting an external circuit conductor to said terminal bar.
- 45 5. An expansible electrode having a large ratio of surface area to volume and readily cleanable which comprises a corrugated star-shaped tube, a terminal bar extending longitudinally through said tube from the axis through the root of one of the corrugations with longitudinal sections of said tube folded outwardly facing opposite sides of said terminal bar, means for securing said terminal bar to one of said longitudinal folded sections, means for releasably interlocking said bar and the other of said longitudinal folded sections to form a rigid corrugated tube, and carrying means and electrical connecting means
- 50 55 60 65 70 75

carried by said terminal bar beyond the plane of
the end of said tube.

JAMES D. COVINGTON.
